UNITED STATES PATENT OFFICE.

MARY C. KERSEY, OF AMO, INDIANA.

BUCKET.

1,074,122.

Specification of Letters Patent. Patented Sept. 30, 1913.

Application filed January 16, 1913. Serial No. 742,509.

To all whom it may concern:

Be it known that I, MARY C. KERSEY, a citizen of the United States, residing at Amo, in the county of Hendricks and State 5 of Indiana, have invented a new and useful Bucket, of which the following is a specification.

This invention relates to an improved form of bucket adapted to be used in the 10 gathering of maple sap and has for an object to provide a bucket which will be light in weight, strong in construction, and adapted to be hung upon a pipe leading from the sap bearing tree.

15 With the foregoing and other objects in view which will appear as the description proceeds, the invention resides in the combination and arrangement of parts and in the details of construction hereinafter described 20 and claimed, it being understood that changes in the precise embodiment of the invention herein disclosed, can be made within the scope of what is claimed, without departing from the spirit of the invention.

25 In the drawings accompanying this specification and forming a part thereof, the preferable form of my invention is illustrated, in which—

Figure 1 is a view in elevation of my 30 proved form of bucket in position upon a sap bearing tree. Fig. 2 is a cross sectional view in elevation of the bucket. Fig. 3 is a cross sectional view taken on the line A—A of Fig. 2.

35 Referring to the drawings in which similar reference numerals designate corresponding parts throughout the several views, the body of the bucket is substantially frustoconical in outline and is composed of the 40 side walls 1 and the bottom 2 which is rigidly attached thereto. The upper edge of the body of the bucket is formed with a ring therearound formed by curling or bending the side walls 1 upon themselves as at 3.

45 Hingedly mounted upon the upper reinforcing ring 3 is a lid 4, this lid being spheric segmental in outline and overlies the reinforcing ring 3 as illustrated more clearly in Fig. 2.

50 The spheric segmental lid 4 is hingedly mounted upon the body of the bucket by means of the hinge 5. Attached to the diametrically opposite portion of the said lid is a retaining clip 6 which is adapted to fit 55 with-over and engaging a projecting lug 7 which projecting lug is held in position by

means of a circular plate 8 rivetedly attached to the bucket wall. In order that the bucket may be conveniently carried, it is provided with the usual bail 9 which bail pivotally engages a reinforcing member upon the bucket wall as at 9. In order that the bucket may be easily and readily mounted upon a spout or tube leading from the sap bearing tree, a suitable opening is provided in the side wall of the bucket at 10 into which opening is rigidly mounted a bearing 13 which is provided with an outstanding annular flange 12 which annular flange is adapted to be held rigidly to the 60 side walls of the bucket by rivets or other suitable means. As will be apparent from Fig. 1, the tube 11 which is embedded in the tree is adapted to project within the bearing 13 to thereby support the bucket thereon. Thus it will be apparent that the entire bucket is adapted to be supported upon the tube 11, which supporting means will allow the bucket to be readily disengaged therefrom and carried to the place to which 65 the sap is to be collected. The bucket having been emptied may be readily reinserted upon the tube support 11 which operation may be easily and quickly performed. My improved sap receiving bucket will therefore be efficient and convenient in use, the structure being such that it may be readily manufactured and by reason of the particular configuration of the lid, any and all liability of dirt or other objectionable material 70 entering the bucket and thereby rendering the sap impure will be eliminated. The construction of the lid is also one which possesses the greatest strength with the minimum amount of material therein. Suitable 75 means have been supplied for hingedly mounting the lid upon the bucket body and also a suitable catch for retaining the lid in a closed position when the bucket is mounted upon the sap bearing tree. 80

Having thus fully described the construction and pointed out the advantages of my improved structure, what I claim to be new and original with me is:—

1. In a sap receiving receptacle, a frustoconical body portion, a spherical segmental lid hingedly mounted upon a reinforcing flange formed integral with the upper edge of said body portion, means for retaining said lid in a closed position, suitable means 85 mounted upon said body portion for carrying said receptacle, said body portion being 90

105

110

provided with an opening adjacent its upper edge, a tubular support provided with a centrally located integral flange, said flange being rigidly held to said body portion to 5 thereby rigidly hold said tubular support within said opening.

2. A sap gathering receptacle comprising a body portion, a lid projecting over the side walls thereof and hingedly secured thereto, 10 means for retaining said lid in a closed position, a bail secured to said body portion, said side walls provided with an aperture adjacent the upper extremity thereof, a sup-

porting member comprising a hollow shank and flange and secured to the inside of said 15 side walls and with the hollow shank extending through the said aperture, said supporting member adapted to receive a sap delivering spout therein.

In testimony that I claim the foregoing as 20 my own, I have hereto affixed my signature in the presence of two witnesses.

MARY C. KERSEY.
